US00D699069S

(12) **United States Design Patent**
Emrick et al.

(10) **Patent No.:** **US D699,069 S**
(45) **Date of Patent:** **** Feb. 11, 2014**

(54) **HANDLE**

(75) Inventors: **Sarah Marie Emrick**, St. Paul, MN (US); **Jared Paul Kreuzer**, Minneapolis, MN (US)

(73) Assignee: **Target Brands, Inc.**, Minneapolis, MN (US)

(**) Term: **14 Years**

(21) Appl. No.: **29/424,305**

(22) Filed: **Jun. 11, 2012**

(51) **LOC (10) Cl.** **07-02**

(52) **U.S. Cl.**

USPC **D7/395**

(58) **Field of Classification Search**

(57) **CLAIM**

The ornamental design for a handle, as shown and described.

DESCRIPTION

FIG. 1 is a front, perspective view of a handle showing a first embodiment of our new design;

FIG. 2 is a front view thereof;

FIG. 3 is a rear view thereof;

FIG. 4 is a right side view thereof, the left side view being a mirror image of the right side view;

FIG. 5 is a top view thereof; and,

FIG. 6 is a bottom view thereof.

The broken lines are for illustrative purposes only and form no part of the claimed design.

1 Claim, 2 Drawing Sheets
